UNITED STATES PATENT OFFICE.

ADOLF GRAF VON BUONACCORSI DI PISTOJA, OF VIENNA, AUSTRIA-HUNGARY.

FIRING MECHANISM FOR TORPEDOES.

SPECIFICATION forming part of Letters Patent No. 417,206, dated December 10, 1889.

Application filed November 15, 1888. Serial No. 290,967. (No model.) Patented in Germany February 24, 1888, No. 45,368; in France February 24, 1888, No. 188,945; in Belgium March 12, 1888, No. 81,003; in Sweden March 12, 1888, No. 1,697; in England March 20, 1888, No. 4,297; in Italy March 31, 1888, XXII, 23,135, XLV, 431; in Portugal May 17, 1888, No. 1,244; in Norway May 28, 1888, No. 934; in Austria-Hungary June 26, 1888, No. 8,093 and No. 21,102, and in Spain June 30, 1888, No. 8,035.

To all whom it may concern:

Be it known that I, ADOLF GRAF VON BUONACCORSI DI PISTOJA, a subject of the Emperor of Austria-Hungary, a residing at Vienna, in the Province of Lower Austria, in the Empire of Austria-Hungary, have invented certain new and useful Improvements in Firing Mechanism for Torpedoes, (for which I have obtained Letters Patent in Austria-Hungary, dated June 26, 1888, No. 8,093, and No. 21,102; in Germany, dated February 24, 1888, No. 45,368; in France, dated February 24, 1888, No. 188,945; in Belgium, dated March 12, 1888, No. 81,003; in Italy, dated March 31, 1888, Reg. Gen., Vol. XXII, No. 23,135, and Reg. Att., Vol. XLV, No. 431; in Spain, dated June 30, 1888, No. 8,035; in Portugal, dated May 17, 1888, No. 1,244; in England, dated March 20, 1888, No. 4,297; in Sweden, dated March 12, 1888, No. 1,697, and in Norway, dated May 28, 1888, No. 934;) and I do hereby declare the following to be a full, clear, and exact description of the invention, such as will enable others skilled in the art to which it applies to make and use the same, reference being had to the accompanying drawings, and to letters or figures of reference marked thereon, which form a part of this specification.

Referring to the drawings, Figure 1 is a vertical longitudinal section of a portion of the bow or striking-point of the torpedo and a portion of the charge-chamber. Fig. 2 is a side elevation of a portion of the firing-pin. Fig. 3 is a section on line *x* *x* of Fig. 2, and Fig. 4 is an isometric view of the portion of the firing-pin, shown in Fig. 2. Fig. 5 is a side elevation, and Fig. 5^a is an end elevation, of the striking-head of the firing-pin detached.

This invention relates to self-propelling, offensive, or fish torpedoes, and in this class of torpedoes of usual construction the explosion follows invariably on the torpedo meeting with sufficient resistance to cause the firing-pin to explode the percussion-cap or fulminate or percussion-primer, irrespective of the distance traveled by the torpedo—that is to say, in all torpedoes of this class with which

I am acquainted the firing-pin is always in position to do its work.

The object of my invention is to provide means whereby the firing-pin will be held against operation until the torpedo has traveled a given distance, thus practically providing a time-fuse differing only from the ordinary time-fuse in that there will be no explosion in case the torpedo should miss its aim—that is, in case the torpedo should not meet with sufficient resistance to its progress to cause the firing-pin to explode the primer.

A further object of this invention is to so construct the firing mechanism as to render its operation entirely independent of any other mechanism of the torpedo, thus dispensing with the long transmission-rods usually employed, which rods extend in some systems of torpedoes from stern to stern, and at the same time to materially increase—in fact, to nearly triple—the distance at which torpedoes have heretofore been rendered effective.

To these ends the invention consists in the combination, with the charge-chamber of a torpedo, of a firing mechanism comprising, essentially, a firing pin or bolt having a free longitudinal and a rotary motion in its bearings, in combination with a time-lock operating to retard or check said free longitudinal motion of the bolt and automatically release the same after the torpedo has traveled a given distance, substantially as hereinafter fully described, and set forth in the claims.

The invention further consists in the combination, with the firing pin or bolt adapted to move freely in a longitudinal direction in its bearings, of a time-lock operating to retard or check said longitudinal motion, and means for imparting a rotary motion to the firing pin or bolt to control the time-lock, substantially as hereinafter fully described, and as pointed out in the claims.

The invention further consists in details of construction and combinations of parts, substantially as hereinafter described, and as set forth in the claims.

As shown in the drawings, the firing-bolt a' , on which is formed the firing-pin a , is provided at its rear end with a helical groove a^2 , into which project the points of two small screws $a^3 a^3$, Fig. 1, screwed into the cone-shaped torpedo-bow a^4 . These screws serve the purpose of locking the firing-bolt against free endwise motion in its bearings without completely checking such motion and to time such gradual endwise motion according to the distance the torpedo has to travel, and then to lock said bolt against rotary motion and permit its free endwise motion in its bearings. To these ends the firing-bolt is provided in front of the helically-threaded portion with an unthreaded portion, in which are formed longitudinal grooves a^21 , the rear ends of which merge into the terminal of the helical groove.

To the front end of the firing-bolt is screwed the striking-point a^4 , that has four striking-arms a^5 , which latter are constructed in the form of propeller-blades of very high pitch, so that as soon as the torpedo is launched the striking-head will revolve, and with it the firing-pin, which will thus be gradually screwed into the firing-chamber a^22 . When the torpedo has traveled a given distance, which will depend on the pitch of both the propeller-blades a^5 and of the helical groove a^2 , the points of the screws a^3 will enter the longitudinal grooves a^21 , thus leaving the firing-pin free to slide longitudinally within its bearings, being guided in its motion by the stop-screws and ready to explode the percussion-priming on meeting with sufficient resistance to its course through the water. If, for instance, the efficient angle of the propeller-blades a^5 is $a = 85^\circ 42' 20''$, the radius $r = 50^{\text{mm}}$, resulting in a linear pitch $r \cdot \text{tg } a = 50 \text{ tg } 85^\circ 42' 20''$, each revolution of the propeller would correspond to a theoretical distance of four meters, provided there is no slip; but, as in this case the slip is at least fifty per centum, the distance will be double, or equal to eight meters. Now, if the torpedo is to be secured against premature explosion until it has traveled a distance of one hundred and twenty meters, the helical groove a^2 must have 120 : 8 = 15 convolutions, while the firing-bolt should be so adjusted that the locking-screws a^3 will be in engagement with the first or initial convolution of the groove. When the torpedo has traveled over this distance, the locking-screws will enter the grooves a^21 and allow the firing-bolt to slide freely in its bearings, while the said bolt is now held against rotation by the locking-screws. If the torpedo strikes the target, the firing-bolt a' will be forced backward and the firing-pin will penetrate through the opening of the cap a^6 and explode the fulminate a^7 , the jet of fire of which, passing through the axial aperture of the firing-ring a^8 , will ignite the explosive a^9 . As usual, an initiative charge of dry gun-cotton contained within a sheet-metal case is exploded by the means referred

to, and through the latter the main charge C of wet gun-cotton.

In Fig. 1 the central portion of the chamber containing the main charge of wet gun-cotton is partly broken away.

Having described my invention, what I claim is—

1. In a firing mechanism for torpedoes, a firing-bolt adapted to have a free longitudinal and rotary motion in its bearings, provided with means for revolving it, and provided with circumferential spiral grooves, and separate and distinct longitudinal peripheral grooves which open into the terminal spiral groove, and suitable points fixed in the bow of the torpedo adapted to enter said grooves, substantially as described, for the purpose specified.

2. In a firing mechanism for torpedoes, a firing-bolt adapted to have a free longitudinal and rotary motion in its bearings, provided at one end with a circumferential spiral groove having the number of its convolutions determined as stated and terminating in separate longitudinal peripheral grooves extending toward its striking end, in combination with suitable stop-points in the torpedo-bow, and propeller-blades for said bow having a pitch determined relatively to the number of the spiral convolutions, substantially as described.

3. In a firing mechanism for torpedoes, a cylindrical firing-bolt having a surface groove consisting of a spiral portion terminating at different points in longitudinal separate and distinct branches, in combination with fixed stops in the bow of the torpedo standing at right angles to the axis of said bolt and adapted to enter said groove, and suitable means for revolving said firing-bolt, substantially as described, for the purpose specified.

4. In a firing mechanism for torpedoes, a firing-bolt provided at one end with propeller-blades and at the other end with a firing-pin, and between these with circumferential spiral grooves, terminating in longitudinal peripheral grooves, in combination with fixed screw-points a^3 in the bow of the torpedo adapted to enter and travel within said grooves, substantially as described, for the purpose specified.

5. In a firing mechanism for torpedoes, the combination of a firing-bolt provided with means for revolving it, and a fixed bearing in the bow of the torpedo, one of said parts being provided with a circumferential spiral groove and longitudinal grooves which form a continuation of the same, and the other part being provided with points which enter and travel in said grooves, substantially as described, for the purpose specified.

6. In a firing mechanism for torpedoes, a longitudinally-movable and revoluble firing-bolt provided with propeller-blades on its outer end, a circumferential spiral groove on its inner end, and intermediate longitudinal peripheral grooves opening into said spiral

grooves, in combination with the fixed studs a^3 in the torpedo-bow, adapted to project into the said spiral and longitudinal grooves, substantially as described, for the purposes specified.

- 5 7. In a firing mechanism for torpedoes, a firing-bolt having both the striking-point a^4 and propeller-blades at one end, the firing-pin a and a spiral, circumferential groove at 10 the opposite end, and intermediate longitudinal peripheral grooves merging into the spi-

ral groove, in combination with the fixed studs a^3 in the torpedo-bow and the firing-chamber, substantially as and for the purposes specified.

In testimony whereof I affix my signature in presence of two witnesses.

Corrections in Letters Patent No. 417,206.

It is hereby certified that in Letters Patent No. 417,206, granted December 10, 1889, upon the application of Adolf Graf von Buonaccorsi di Pistoja, of Vienna, Austria-Hungary, for an improvement in "Firing Mechanism for Torpedoes," errors appear in the printed specification requiring the following corrections, viz: On page 2, line 95, the words *engaging said grooves* should be inserted after "torpedo-bow," and the last word in said line should read *bolt* instead of "bow"; and that the said Letters Patent should be read with these corrections therein that the same may conform to the record of the case in the Patent Office.

Signed, countersigned, and sealed this 17th day of December, A. D. 1889.
